OF ST. LOUIS, MISSOURI

FEEDING MECHANISM FOR NUT-CRACKING MACHINES AND THE LIKE

Application filed February 1, 1928. Serial No. 250,975.

This invention relates generally to feeding mechanisms, and more particularly to feeding mechanisms for nut cracking machines and the like, the predominant object of the invention being to produce a feeding mechanism which is simple in construction and which when in use will feed edible nuts positively and rapidly to the cracking elements of a nut cracking machine.

10 Figure 1 is a view of my improved feeding mechanism shown partly in elevation and partly in vertical section, the elements by which said mechanism is supported being shown in section;

15 Figure 2 is a plan view of the mechanism shown in Fig. 1, portions of the supporting elements being broken away to conserve space and fragments of the cracking elements or dies of a nut cracking machine being shown 20 to illustrate the arrangement of the feeding mechanism with respect thereto;

Figure 3 is a cross-section of the feeding mechanism;

Figure 4 is a fragmentary view showing 25 the mechanism for operating one of the shuttles of the feeding mechanism.

In the drawing, which illustrates one embodiment merely of my invention, A designates spaced-apart supporting elements 30 which, if desired, may be parts of the frame of the nut cracking machine with which the feeding mechanism is associated. B designates a member which includes a pair of vertically disposed side walls 1, spaced apart 35 from each other as shown clearly in Figs. 2 and 3, the opposite ends of each of said side walls being secured by means of suitable fastening devices such as bolts 2, to the respective supporting elements A, said side walls preferably being provided with suitably shaped flanges formed thereon through which said fastening devices pass. Interposed between the side walls 1 of the member B is a pair of upwardly extended walls 2', each of said walls comprising an intermediate vertical portion 3, an inclined upper portion 4, and a downwardly curved portion 5. The inclined upper portions 4 of the walls 2' meet at the upper edge of the member B, as shown in Fig. 1, and the por-

tions 4 and 5 of each wall 2' are provided with concave faces so that each wall 2' has a concave face 6 which extends continuously from the upper end of the portion 3 to the lower end of the portion 5. The walls 2' may be formed integral with the walls 1, or, if desired, said walls 2' may be separate elements secured to the walls 1 in any convenient manner to produce a unitary structure.

Mounted for rotation between the side walls 1 of the member B at points between the respective walls 2' and the opposite ends of said member, is a pair of rotary feeding elements 7, each of said rotary feeding elements comprising a plurality of radial wings 60 provided each with a concave face 8 (Figs. 1 and 2), and each of said wings having a curved outer end 9 (Figs. 2 and 3), the curvature of which corresponds approximately to the curvature of the concave faces 6 of the walls 2' (see Fig. 2). The curvature of the downwardly curved portions 5 of the walls 2' is such that their centers approximately coincide with the axes of the rotary feeding elements 7, and in view of this arrangement, 65 it is obvious that when the feeding elements 7 are being rotated, the curved outer ends of the wings thereof will move along the curved faces of the wall portions 5 in close proximity thereto.

70 The rotary feeding elements 7 are each fixedly mounted on a shaft 10 which is rotatably supported by the side walls 1 and at one end of each of said shafts 10, a bevel gear 11 is fixed thereto. The bevel gears 11, as shown 75 clearly in Fig. 2, mesh with bevel gears 12 mounted on a drive shaft 13, which drive shaft 13 is subjected to axial rotation through the instrumentality of suitable motion-transmitting means operatively connecting said 80 shaft to a moving part of the nut cracking machine (not shown) with which the feeding mechanism is associated, or if desired, said drive shaft 13 may be driven by means separate from the nut cracking machine.

85 Located below each of the rotary feeding elements 7 is a shuttle 14 each of which is pivotally supported by the side walls 1 at the point designated by the reference character 15, there being a shaft 16 to which the shuttle 100

is fixed rotatably supported by the side walls 1 at this point. Each of the shuttles is provided with a concave face 17 of a shape to receive an edible nut, and when the shuttles are in their elevated or closed positions, the concave faces 17 thereof are located immediately at the lower ends of the concave faces 6 formed on the walls 2' (Fig. 1). Each of the shuttles 14 has associated with it a contractile coil spring 18, the opposite ends of which are attached to the shuttles and to one of the supporting elements A or to some other fixed part. The tendency of the coil springs 18 is to draw the shuttles downwardly and rearwardly to an open position, as shown in dotted lines in Fig. 4.

Fixedly mounted on each of the shafts 10 which support the rotary feeding elements 7 is a cam 19, said cams being interposed between the bevel gears 11 fixed on the shafts 10 and the adjacent side wall 1. The cams 19 each have the shape illustrated in Figs. 1 and 4, and, of course, rotate with the shafts 10 on which they are mounted. Fixed at an end of each of the shafts 16 which support the shuttles 14 is an arm 20, said arms being so located on said shafts that they are arranged immediately below and in vertical alinement with the cams 19. Also, each of the shuttles 14 is provided with a pin 21, said pins each being located with respect to the adjacent parts of the mechanism, as shown in Fig. 3, and each of the wings of the rotary elements 7 being cut away, as shown at the points designated by the reference character 22 in Fig. 3 to permit said wings to move with respect to said pin 21 without striking same.

Arranged to the rear of the member B, as shown in Fig. 3, is a hopper 23 adapted to receive the edible nuts to be fed by the mechanism disclosed herein to the nut cracking machine with which said mechanism is associated, said hopper being provided with an inclined wall 24 and having an opening 25 at its bottom. 26 designates endless sprocket chains which operate over sprocket wheels 27 and sprocket wheels 28 at the upper and lower portions, respectively, of the hopper 23, said chains being spaced apart, as shown in Fig. 2, so that they will discharge nuts into the compartments within the member B in which the respective rotary elements 7 are located. The sprocket chains 26 and the sprocket wheels 27 and 28 are arranged that the flights 26' of said sprocket chains pass upwardly through the hopper in contact with the inclined wall 24 thereof, said sprocket chains passing through the opening 25 at the lower end of said hopper. The sprocket chains 26 each has attached to it a plurality of buckets 29 spaced equidistant throughout the length thereof, and interposed between each adjacent pair of buckets 29 of each sprocket chain and fixed to said sprocket

chain 26 is a nub 30. The sprocket wheels 27 and 28 are, of course, fixedly mounted on rotatable shafts which are suitably supported, and motion is imparted to one of said shafts by suitable means which may be cooperatively connected to moving parts of the nut cracking machine with which the feeding mechanism is associated, whereby the sprocket chains will be driven. It is obvious, of course, that if desired, the sprocket chains may be driven by means separate from the nut cracking machine.

Fixed to the hopper 23 adjacent to the opening 25 at the bottom thereof is a flexible gate 31. This gate is fixed at the point indicated by the reference character 32 to the hopper and normally extends across the opening 25 so that all of said opening except those portions thereof which are occupied by the sprocket chains 26 is closed. The gate 31 is so shaped and is formed of such resilient material that it may be flexed to permit the nubs 30 and the buckets 29 on the sprocket chains 26 to pass through the opening 25 as said sprocket chains are in motion, and said gate will immediately snap back to its normal position after a bucket or nub has passed beyond same, so as to prevent escape of nuts from the hopper through the opening 25. In view of this arrangement, it is plain that the opening 25 will always be closed against the passage of nuts therethrough.

While the feeding mechanism disclosed herein may be used with great efficiency with a number of nut cracking machines now in common use, it is intended particularly for use with the nut cracking machine disclosed in an application for U. S. Letters Patent bearing Serial No. 221,980, filed by me on September 26th, 1927. The nut cracking machine disclosed in the application for patent referred to is a double-acting machine, said machine having a pair of stationary nut cracking elements or dies with respect to which a pair of reciprocating nut cracking elements or dies move, and the nuts are cracked between the co-operating dies as the reciprocating dies move into close proximity to the stationary dies. In the drawing, I have illustrated only enough of the nut cracking machine to enable a clear understanding of the operation of the feeding mechanism to be obtained, the stationary nut cracking elements or dies of the nut cracking machine being designated by the reference character C, said dies being supported by a portion D of the frame of the machine. Also, in the drawings, E designates the reciprocating nut cracking elements or dies which move toward the stationary dies C to crack the nuts therebetween. The reciprocating dies, as shown clearly in Fig. 1, are located so that they reciprocate immediately above the concave faces 17 of the shuttles 14, the side walls 1 being provided with openings 1' formed

therethrough, through which said dies may extend.

In the operation of my improved feeding mechanism, nuts will be placed in the hopper 23 and the sprocket chains 26 will be set in motion. As the buckets 29 on the sprocket chains 26 pass through the nuts in the hopper, each bucket will pick up a nut, the nubs 30 preventing more than one nut being carried by a single bucket. As each bucket reaches the point where it passes over the associated sprocket wheel 27, the nut carried thereby will roll from said bucket and said nut will fall between the end walls 1 of the member B and will drop between a pair of wings on the associated rotary feeding element 7. The rotary feeding element will at this time be rotating in the direction indicated by the arrows in Fig. 1 and the nut 20 will be carried downwardly by said rotary feeding element, said nut being rolled slowly as the rotary feeding element is rotated along the concave face 6 of the associated wall 2', and this rolling action, together with the 25 shape of the concave face 6, and the concave faces on the wings of the rotary feeding element, will cause the nut to rotate about its major axis instead of rolling over end for end. When the wing of the rotary feeding element which is carrying the nut reaches its 30 lowermost position, the nut is deposited on the concave face 17 of the associated shuttle which at this time will be in position to receive said nut and the rotary feeder wing 35 which carried said nut downwardly will continue its rotary movement upwardly. The operation of the nut cracking machine is so timed that immediately as the nut is deposited on the shuttle 14, the associated reciprocating die E moves toward the associated stationary die C, and as the nut is interposed between the co-operating ends of said dies, the shell of said nut will be cracked. The 40 shuttle 14 is maintained in its elevated position by the arcuate faces 19' of the cam 19 contacting with the arms 20, as shown in Fig. 1, and immediately as the nut is gripped by the dies C and E, the arcuate face 19' of the cam which was in contact with the arm 45 20 will pass beyond said arm and thereby permit the coil spring 18 to swing the shuttle downwardly in the arc of a circle so that the nut will be discharged downwardly from the dies on being cracked; when the shuttle has 50 been swung downwardly as described, it will be in the position in which it is shown in Fig. 4, and the straight faces 19^b of the rotating cam 19 will then pick up the arm 20, swinging it in an arc of a circle, thereby rotating the shuttle to its elevated position, when it 55 will receive the next nut carried downwardly by the associated rotary feeder 7. This operation is continued during the operation of the feeding mechanism, each nut being carried downwardly by a rotary feeder and be-

ing deposited on the associated shuttle where it is cracked by the dies of the nut cracking machine, and the shuttle then being tripped to discharge the cracked nut.

It sometimes happens that a cracked nut will adhere to the ends of the dies after the cracking operation, and if this should happen, said nut will be struck and dislodged by one of the pins 21 which pass between the co-operating dies immediately after the shuttle has been released and before the reciprocating dies have been completely retracted.

While I have shown and described a feeding mechanism intended for use with a double-acting nut cracking machine, it is to be understood that I do not limit myself to such an arrangement, as it is obvious that I may construct feeding mechanisms intended for use with a nut cracking machine having a single nut cracking unit, and also that I may construct feeding mechanisms adapted for use with nut cracking machines having more than two nut cracking units.

I claim:

1. Feeding mechanism comprising a rotary element, feeding means for conducting articles to be fed to said rotary element, a member arranged to receive articles from said rotary element, the last mentioned member being trippably supported to effect the discharge therefrom of articles being fed, and means for tripping said member.

2. Feeding mechanism comprising a rotary element having a plurality of radial wings, a curved face with respect to which said wings move in close proximity thereto, feeding means for conducting articles to be fed to said rotary element, a member arranged to receive articles from said rotary element, said member being trippably supported to effect the discharge therefrom of articles being fed, and means for tripping said member.

3. Feeding mechanism comprising a rotary element having a plurality of radial wings, a face curved in the direction of travel of said rotary element and concave in a direction transverse to such direction of travel, said wings being movable with respect to said face and in close proximity thereto, feeding means for conducting articles to be fed to said rotary element, a member arranged to receive articles from said rotary element, said member being trippably supported to effect the discharge therefrom of articles being fed, and means for tripping said member.

4. Feeding mechanism comprising a rotary element having a plurality of radial wings each of which is provided with a concave face, a face curved in the direction of travel of said rotary element and concave in a direction transverse to such direction of travel, said wings being movable with respect to the last mentioned face and in close proximity thereto, feeding means for conducting articles to be fed to said rotary element, a mem-

ber arranged to receive articles from said rotary element, said member being trippably supported to effect the discharge therefrom of articles being fed, and means for tripping said member.

5. Feeding mechanism comprising a rotary element having a plurality of radial wings each of which is provided with an arcuate outer edge, a face curved in the direction of travel of said rotary element and concave in a direction transverse to such direction of travel, the curvature at the outer edges of said wings being approximately coincident with the curvature of said concave face, and the curved edges of said wings being movable with respect to said curved and concave face in close proximity thereto, feeding means for conducting articles to be fed to said rotary element, a member arranged to receive articles from said rotary element, said member being trippably supported to effect the discharge therefrom of articles being fed, and means for tripping said member.

6. Feeding mechanism comprising a rotary element having a plurality of radial wings each of which is provided with an arcuate outer edge and a concave side face, a face curved in the direction of travel of said rotary element and concave in a direction transverse to such direction of travel, the curvature at the outer edges of said wings being approximately coincident with the curvature of the last mentioned concave face, and the curved edges of said wings being movable with respect to said curved and concave face in close proximity thereto, feeding means for conducting articles to be fed to said rotary element, a member arranged to receive articles from said rotary element, said member being trippably supported to effect the discharge therefrom of articles being fed, and means for tripping said member.

7. Feeding mechanism comprising a rotary element having a plurality of radial wings each of which is provided with an arcuate outer edge, a face curved in the direction of travel of said rotary element and concave in a direction transverse to such direction of travel, the curvature at the outer edges of said wings being approximately coincident with the curvature of said concave face, and the curved edges of said wings being movable with respect to said curved and concave face in close proximity thereto, feeding means for conducting articles to be fed to said rotary element, said feeding means comprising an endless traveling element provided with a plurality of carriers, a hopper through which said endless traveling element travels, a member arranged to receive articles from said rotary element, said member being trippably supported to effect the discharge therefrom of articles being fed, and means for tripping said member.

8. Feeding mechanism comprising a rotary

element having a plurality of radial wings, a curved face with respect to which said wings move in close proximity thereto, feeding means for conducting articles to be fed to said rotary element, a member arranged to receive articles from said rotary element, and means including a cam for tripping said member to effect discharge therefrom of articles being fed.

9. Feeding mechanism comprising a rotary element having a plurality of radial wings, a curved face with respect to which said wings move in close proximity thereto, feeding means for conducting articles to be fed to said rotary element, a member arranged to receive articles from said rotary element, an arm movable with said member, means tending to move said member to its open position, and a rotary cam co-operating with said arm and arranged to maintain said member in its closed position, said cam being operable to permit the last mentioned means to move said member to an open position when an article supported thereby will be discharged therefrom.

In testimony whereof, I have hereunto set my hand.

LEO J. MEYER.
